No. 784,174.

PATENTED MAR. 7, 1905.

F. H. PARKHURST.
SKIRT HANGER.
APPLICATION FILED MAY 26, 1904.

UNITED STATES PATENT OFFICE.

FREDERIC H. PARKHURST, OF BANGOR, MAINE, ASSIGNOR TO THE J. F. PARKHURST & SON COMPANY, OF BANGOR, MAINE, A CORPORATION OF MAINE.

SKIRT-HANGER.

SPECIFICATION forming part of Letters Patent No. 784,174, dated March 7, 1905.

Application filed May 26, 1904. Serial No. 209,823.

To all whom it may concern:

Be it known that I, FREDERIC H. PARKHURST, a citizen of the United States, residing at Bangor, in the county of Penobscot and State 5 of Maine, have invented an Improvement in Skirt-Hangers, of which the following description, in connection with the accompanying drawings, is a specification, like letters on the drawings representing like parts.

10 This invention has for its object the production of a novel skirt-hanger which is so constructed that when a skirt is hung thereon it will occupy less room and be held in shape better than when it is supported or hung from 15 the waistband, as is commonly done.

My improved skirt-hanger has been especially designed for use in wardrobe-trunks, as by means of it the length of the space required to support the skirt is very much reduced and 20 the skirt can be hung so that it will not become wrinkled when it is packed.

The skirt-hanger, preferably, has a length about one-half that of an ordinary skirt and a width about equal to half the size of the 25 waistband. At one edge it is provided with some suitable means for attaching the skirt-waistband thereto and the opposite edge is constructed to have the skirt-body folded thereover, said edge constituting what I have

30 termed a "folding edge." Coöperating with the folding edge I preferably employ a suitable clamping means which is adapted to clamp the body of the skirt against said folding edge. When in use, the device is suspended with the folding edge up, and therefore the skirt hangs over said edge and is supported thereby, thus occupying a space only about one-half as long as the skirt is.

Since skirts are larger at the bottom than at 40 the waistband, it will be necessary to fold the skirt longitudinally thereof in order to bring it within the limits of the folding edge. The clamping means, however, serves to hold the longitudinal folds of the skirt in their proper 45 position while the skirt is supported, and thus prevents the skirt from being wrinkled.

In the drawings, Figure 1 is a perspective view of my improved skirt-hanger with the

skirt supported thereby shown in dotted lines. Fig. 2 is a plan view showing the manner of 50 applying a skirt to my improved hanger. Fig. 3 is a detail hereinafter referred to.

In the preferred form of my invention the skirt-hanger is made in the form of a frame comprising the two side bars 3 and the end 55 bars 4 and 5. The end bar 4 preferably carries suitable means to which the waistband of the skirt may be attached, such means in this embodiment of my invention being in the form of hooks 6, adapted to engage the usual 60 hanging-loops 7 with which skirt-waistbands are generally provided. The end bar 5 constitutes what I have termed the "folding bar" 65 or folding edge of my hanger, because when a skirt is supported thereby it is folded over 70 said bar, as will be more fully hereinafter described.

Coöperating with the folding bar 5 is a suitable clamping device, herein shown as a clamping-bar 8, which is hinged at one end to one 75 of the side bars 3 at 9, the other end of said clamping-bar being detachably connected to the other side bar 3. As herein shown, the clamping-bar 8 is notched at its free end, and when it is in operative position the notch of 80 said end receives the projecting end 11 of one of the side bars 3.

12 designates the retaining-strap, which is secured at one end to one side of the side bar 3 and is adapted to be folded over the end of 85 the side bar, as shown in Fig. 1, the other end of said retaining-strap having suitable means, such as an ordinary ball-and-socket fastener 13, to detachably secure it to the said side bar 3.

14 designates a suspending-hook by which the skirt-hanger is suspended.

In applying a skirt to my improved skirt-hanger the retaining-strap 12 is released and the clamping-bar 8 swung into its open position, as shown in Fig. 2. The skirt-waistband is then secured to the bar 4 by suspending the loops 7 upon the hooks 6 and the skirt spread out to its full width. The skirt is then folded longitudinally near its edges, so 95 that the said edges are turned over upon the

body of the skirt, as shown at the right in Fig. 2, this operation reducing the width of the skirt to the width of the skirt-hanger or the length of the folding bar 5. The device 5 is then turned into the position shown in Fig. 1, so that the skirt is folded over and hangs upon the end 5 of the skirt-hanger and at the same time the clamping-bar 8 brought into its operative position and there secured by 10 the retaining-strap 12, as shown in Fig. 1, said bar clamping the body of the skirt against the folding edge 5 and firmly holding the folded-in edges 15 of the skirt in position. The device, with the skirt supported thereby, 15 is then suspended by means of the hook 14.

The clamping-bar 8 serves not only to hold the skirt from slipping off from the folding edge 5, but it also serves to hold the longitudinal folds of the skirt in their adjusted position, and thereby prevents the skirt from being 20 wrinkled or creased.

It will be seen that when a skirt is supported on my improved device the length of the space it occupies is only about one-half the 25 length of the skirt, and the fullness of the skirt is taken care of in such a way that it will not crease or wrinkle.

While I prefer to make my improved skirt-hanger with a frame-like or skeleton construction, since such a construction is very light and yet sufficiently strong, I do not wish to be limited thereto, as the body of the skirt-supporter might be made in any suitable way without departing from the invention.

35 It is not absolutely essential to the invention that the hooks 6 or their equivalents be used on the ends 4 of the device, as after the skirt has been folded over the folding edge 5 and there clamped the skirt will be held in 40 position without the hooks 6. I prefer to use these, however, as they assist materially in getting the skirt properly placed on the device.

The particular form of clamping means 45 herein illustrated is not essential to the invention, but is that which I prefer, owing to its simplicity and effectiveness. It will be obvious, therefore, that very many changes in the construction of the parts may be made 50 without in any way departing from the invention. I regard it as new to provide a skirt-supporter so constructed that the skirt is folded transversely over the folding edge of the device and clamped to said edge, and therefore desire to claim this feature broadly.

55 Having described my invention, what I claim as new, and desire to secure by Letters Patent, is—

1. A skirt-hanger having at one edge means 60 to attach a skirt-waistband thereto, the opposite edge being constructed to have the skirt

folded thereover, and means to clamp the skirt to the edge over which it is folded.

2. A skirt-hanger having a folding edge over which the skirt is folded, and a clamp to 65 hold the fold of the skirt against said edge.

3. A skirt-hanger comprising a frame having skirt-waistband-attaching means at one edge, the opposite edge constituting a folding edge over which the skirt is folded, and means 70 to clamp the skirt against said edge.

4. A skirt-hanger having at one edge means to attach the skirt-waistband thereto, the opposite edge constituting a folding edge over which the skirt is folded, means to clamp the 75 skirt against said edge, and means to suspend the skirt-hanger with the folding edge uppermost.

5. A skirt-hanger comprising a frame having on one side skirt-waistband-attaching 80 means, the opposite side constituting a folding edge, and a clamping-bar coöperating with said folding edge to clamp the skirt in place.

6. A skirt-hanger comprising a frame having on one side skirt-waistband-attaching 85 means, the opposite side constituting a folding edge, a clamping-bar coöperating with said folding edge to clamp the skirt in place, and means to suspend the skirt-hanger with the folding edge uppermost.

90 7. A skirt-hanger comprising a frame provided with side bars and end bars, one of said end bars having means to attach a skirt-waistband thereto, and the other end bar constituting a folding bar over which the skirt is folded, and means to clamp the folded skirt to said folding bar.

8. A skirt-hanger comprising a frame provided with side bars and end bars, one of said end bars having means to attach a skirt-waistband thereto, and the other end bar constituting a folding bar over which the skirt is folded, and a pivoted clamping-bar coöperating with the folding bar to hold the skirt in place.

105 9. A skirt-hanger comprising a frame provided with side bars and end bars, one of said end bars having means to attach a skirt-waistband thereto, and the other end bar constituting a folding bar over which the skirt is folded, a pivoted clamping-bar coöperating with the folding bar to hold the skirt in place, and a suspending-hook projecting from the clamping-bar whereby the device is suspended with the folding bar uppermost.

110 In testimony whereof I have signed my name to this specification in the presence of two subscribing witnesses.

FREDERIC H. PARKHURST.
